3 Sheets-Sheet 3

UNITED STATES PATENT OFFICE.

CHRISTIAN W. SCHLUSING, OF NEW YORK, N. Y.

CENTURY CALENDAR.

Application filed December 7, 1926. Serial No. 153,063.

This invention relates to calendars and has particular reference to that class of calendars which are spoken of commonly in the trade as perpetual.

5 Among the objects of the invention is to provide a mechanical calendar having the adaptability of indicating as a result of a simple adjustment the day of the week of any date desired, within the range of the 10 machine or device, it being my purpose for the range of the device to be sufficiently extensive to cover practically any historical date.

Another object of the invention is to provide a calendar in the nature of an indicator that may be readily adjusted for any desired year or years and for the monthly and weekly indications to be availed of with the least amount of inconvenience, and for the devices 20 to be so set or locked as to be rendered fool-proof and hence possessed of the highest degree of reliability, without which a calendar would be useless.

With the foregoing and other objects in view the invention consists in the arrangement and combination of parts hereinafter described and claimed and while the invention is not restricted to the exact details of construction disclosed or suggested herein, still for the purpose of illustrating a practical embodiment thereof reference is had to the accompanying drawings in which like reference characters designate the same parts in the several views, and in which—

35 Figure 1 is a vertical transverse section showing the interior of the device.

Fig. 1^A is a detail view of the locking means.

Fig. 2 is an end elevation of the device.

40 Fig. 3 is a longitudinal section just within the face plates, looking toward the rear.

Figs. 4 and 4^A considered together are an illustration of the calendar sheet showing the complete layout of all possible months 45 for both common and leap years that may ever be used.

Fig. 5 is a view corresponding to Fig. 3, but showing the principal portions of the face of the calendar and with parts broken 50 away at the left to show the interior con-

struction and especially the brake or locking mechanism.

Fig. 5^A is a detail view of a key.

Figs. 6 and 7 considered together indicate the year plates located at the bottom of the 55 casing.

Fig. 8 is a detail view of the adjustment mechanism for the indicators.

Referring now more specifically to the drawings I show my improvement as comprising a casing 1 having a substantially flat inclined face portion and a curved or ogee-shaped rear portion and mounted upon a base 16 having feet in the nature of rubber cushions or the like shown at 14, the casing being secured to the base by means of tap screws 37 co-operating with lugs 60 secured to or extending downward from the casing. While the several parts of the device may be made of any suitable materials, it is 70 preferable that the casing be made of sheet metal or other strong relatively thin material and for the base to be made of a slab of wood or its equivalent.

The front portion of the casing is provided 75 with a large sight or window 39 of rectangular form and at the upper left and right corners are smaller openings or windows 40 and 41 for the observation respectively of the names of the months and the numbers 80 of the months and the number of days therein. Over the window 40 is printed the legend "Month" 42, and over the window 41 is printed the legend "No Mo Days" 43.

Fitted within the window or sight 39 is a 85 slide 2 within which is formed a rectangular opening or window 66 corresponding to a monthly calendar block and having a length equivalent to seven units corresponding to the seven days of the week indicated at 15 in the usual form "S M T W T F S" marked upon the rim of the slide 2 just above the window 66. Below the window 66 and centrally of the slide is formed a pointer or indicator 44, the purpose of which will soon

90 appear. The length of the window 39 is indicated as of thirteen units as compared with the seven units of the length of the window 66.

95 The slide 2 is adapted to be adjusted from 100

time to time lengthwise of the device or to the right or left as viewed in Fig. 5 by any suitable mechanism manually operated. For this purpose I indicate a threaded rod 5 or screw 3 journaled at its ends 35 and 53 to the ends of the outer casing 1 against movement longitudinally of said rod, and running on the rod 3 is a threaded nut or sleeve 3^a fixed, as shown in Fig. 8, to the inner surface of the slide 2 just below the opening 66, so that when the rod 3 is rotated, the sleeve 3^a, and consequently the slide 2 is caused to move transversely of the machine toward the left or right, according to the direction of rotation of said rod. An auxiliary indicator 12 is secured to the sleeve 3^a or any other suitable portion of the slide 2 and extends downward therefrom into and along a slot 38 formed in the base 16. This indicator 12 co-operates with a transparent plate 13 of glass or its equivalent fixed in the bottom of the base adjacent to a pair of scheduled plates 5 and 6. The slide 2 is guided for its adjustments along a pair of guide ways or keepers 24 and 25 at the upper and lower edges thereof, the same being secured within the front of the main casing in any inconspicuous position. One end of the rod 3 is provided with a socket 53 for an adjusting instrument such as a key 54 for the rotation thereof which determines the right or left adjustment of the plate or slide 2.

One purpose of the slide 2, with its indicators 12 and 44, is to indicate the number of any selected year, whether current or otherwise. A plate 4 fixed upon the front of the main casing 1 carries in seven vertical groups or rows blocks of yearly numbers from 1900 to 2000, both common and leap years, said rows or groups of yearly numbers being arranged in units of width corresponding precisely to the calendar block units above referred to in connection with the window 66, and as indicated in Fig. 5, while the pointer 44 is in its mid position over the central group or row of year numbers, it may be moved one, two or three units either to the right or to the left, to cover any one of the seven groups or rows of numbers in the plate 4, and when the slide 2 is so moved with its indicator 44, the window 66 is similarly moved through one, two, or three units in the same direction. The annual numbers indicated on the plates 4, 5, and 6 are complete only along the upper ends of the rows or groups, and to conserve space the hundreds and thousands digits are omitted elsewhere. It will be understood also that all the yearly numbers in any group or row will be indicated simultaneously according to the adjustment of the pointers 12 and 44, and that the years so numbered in each group are so determined that the calendar pad adjustment for the

months and days of the month will apply to each and every year of any one indicated group or vertical row of years. It will be remembered also that the indicators 12 and 44 are rigidly connected to each other as well as to the slide 2 so that not only will a group of yearly numbers be indicated on plate 4, but also on plates 5 and 6. No confusion, however, arises from this circumstance because the number of the year under consideration will always be pointed out by one of the pointers, and the other will be disregarded. On plate or schedule 5 are indicated common and leap years from 1800 to 1900, the numbers being arranged as before explained in seven vertical groups or rows. Schedule 6 indicates seven rows or groups of years prior to 1800, both common and leap years. These indicators illustrate the nature of the invention, but the scope of the years covered by the invention may of course be varied as may be desired, either for longer or shorter periods, or for the period to extend further than indicated, either forward or rearward. The plates 5 and 6 are shown recessed in a cavity or recess 46 formed in the bottom surface of the base 16. The plate 5 is provided with a slot or opening 45 for visibility of the index 12 therethrough and through the plate 13.

The calendar sheet is indicated at 7 and comprises along its left margin a column 67 of the names of the months of both common and leap years, in the usual order, and along the right hand margin are two vertical columns 68 and 69 indicating the numbers of the months and the number of days therein respectively. The name of any month selected appears through the window 40, and the calendar block associated therewith at such time will appear through the window or opening 66, it being the next block below the block on the same level with the name of the month, this resulting from the fact that the construction is so designed, as shown in Fig. 5, that the number of the month is shown elevated above the calendar block therefor. The sheet or strip 7 is attached at its upper and lower ends to upper and lower rollers 18 and 19 having gears 20 connecting them for simultaneous rotation in opposite directions. The ends of the strip are secured to the rollers by means of wedge-shaped inserts 30 held in place by screws 57 in depressions or recesses 56 formed in the rollers. Fig. 1 indicates the direction of movement of the strip with respect to the rollers and how the strip coils upon one of the rollers simultaneously with its uncoiling from the other. The strip passes over a tube or sleeve 55 mounted on a movable rod 21 to whose ends are attached a pair of springs 22 operating along curved slots 47, the opposite ends of the springs being anchored at 62 in holes in the inner

frame 31. That portion of the sheet 7 which is immediately visible or active is guided and held between a back plate 17 and the face plates. The back plate is shown best in Figs. 1 and 5 and is held in place by means of two tie rods 23 fixed in the end walls of the inner frame 31 so that the sheet is held close to the sight openings in the front casing. The upper and lower edges 10 of the backing plate 17 are shown rolled around the tie rods. The rollers are provided with inner flanges 26 between which the sheet 7 operates and with outer flanges 27 which lie adjacent to the inner frame walls at 31. The upper roller has a trunnion 29 with opening at end operating in a bearing 29* adjacent to which is a finger knob 8 for the manipulation of the rollers by spindle 59. Through the operation of 20 the gears 20, the rotation of the upper roller in either direction will cause a simultaneous rotation of the lower roller in the opposite direction. Beneath the trunnion 29, the lower roller has a trunnion 28, and the rollers at their opposite ends have similar trunnions 28, each of which has bearing at 28* in the inner frame. The knob 8 is intended to be key controlled so as to prevent its being tampered with an unauthorized person. 30 I provide also a safety appliance in the nature of a hub 52 at the end of the lower roller remote from the knob 8 as shown in Figs. 1^a and 5. The hub 52 has a serrated surface with which co-operates a similarly formed shoe 51 carried by a spring 50. This shoe is backed up on the opposite side of the spring by means of a multiple cam 48 mounted upon a spindle 49. This spindle has a key socket 33 accessible from the 35 left end of the casing, and upon rotation of the spindle and cam wheel 48 through 60°, one of the cams will thrust the shoe into locking contact with the hub 52 or to the position shown in Fig. 1^a. A further rotation through 60° will release the shoe so as to permit the rollers to be rotated or adjusted through manipulation of the knob 8. I prefer to insure that the spindle 49 shall be rotated always in one direction only, 40 and for this purpose I provide a pawl 64 and ratchet wheel 32 shown in Figs. 1 and 5. The pawl is held in place resiliently by means of a spring 63.

The inner frame 31 is secured to the base 55 by screws 36 which for the sake of delicacy of adjustment longitudinally operate through slots 65.

The windows or openings 39, 40, and 41 are preferably fitted with strong transparencies such as glass lenses 9, 10, and 11 respectively for clear visibility and to protect the inner parts of the structure from being handled, soiled, or broken. At the front of the casing I provide also a pen and pencil 60 tray or rack 84.

With the foregoing specific description of the mechanism, the manner of manipulation and operation thereof may be briefly summarized as follows: For practical use as a desk calendar for which the device is well adapted, the slide 2 is so adjusted endwise as to bring the pointer 44 over the vertical row or column of year numbers in which the desired year is found. For the current year, for instance, the pointer 44 would be 70 found over the third column from the left or the one headed by the number 1909 in which group the current year is found. The knob 8 is then rotated to bring into view at the window 40 the name of the current 75 month, the operator taking care to observe that the name of the month is selected in that portion of the strip 7 according to whether the year is a leap year or a common year. The current year being a common one, 80 the selection will be taken from the upper end of the strip. The proper block indicating the days of the month will appear in the window 66, and in proper relation to the days of the week "S" to "S" indicated 85 thereover. The foregoing directions as to the manipulation of the device as a practical desk calendar will be applicable to the determining of the day of the week of any date within the scope of the arrangement. 90 More specifically, if it is desired to determine the day of the week in which the Fourth of July fell during the year 1901, which was a common year, the parts being unlocked or released, the operator adjusts 95 the slide 2 by rotation of the screw 3 so as to bring the pointer over the column of yearly numbers headed by 1901, the sixth unit from the left on the schedule plate 4. The window 66 then discloses units 6 to 12 inclusive. The knob 8 is then rotated so as to bring the name of the month, July, at the upper portion of the strip 7 into view at the window 40, thus bringing the monthly block, 100 the one below the name "July", into view at 105 the window 66 with the sixth unit thereof at the left and with the indication that the fourth day of July will register with the fifth day of the week or Thursday, which was to be determined. All this is accomplished by the simple adjustment of the mechanism, first for the year, and then for the month of that year. It follows from this description that the plate or slide 2 requires adjustment but once for each year, 110 while the calendar sheet 7 requires adjustment once for each month.

For the convenience of the user, the common and leap year portions of the strip 7 may be distinguished from each other by 115 different colors or shades of material or coloring applied thereto and likewise the annual schedule plates 4, 5, and 6 may have their common and leap year portions respectively tinted or colored to correspond to the 120

coloring of the sheet or strip 7. I wish to point out also that the grouping of the year numbers in particular columns, with a plurality of years in each column, all having the same characteristics of monthly and weekly adaptation in each column, is a matter of distinct importance and is believed to be unique with this invention. Furthermore, the arrangement of the year numbers in each column or group may obviously be varied and may either be in numerical order or otherwise as may be thought best.

I claim:

1. In a century calendar, mechanism comprising a sheet bearing individual blocks of monthly numerals in complete series for both common and leap years, means to mount the sheet for endwise adjustment according to the month selected and the year, transversely movable means to obscure the monthly blocks except for a single definite selected month, and year indicating means movable with the obscuring means aforesaid to correlate the year and selected month coincident with the transverse movement of the obscuring means.

2. A construction as set forth in claim 1 in which the means to mount the sheet comprises a pair of rollers so connected that the rotation of one will cause the rotation of the other in the opposite direction whereby the sheet will be rolled upon one roller and from the other, said obscuring means consisting of a plate having a window and overlying the sheet and mounted on a transversely extending adjusting screw.

3. In a calendar of the character set forth, the combination of a casing having a large front window, a year schedule fixed within a portion of said window, a slide within the casing adjacent and communicating with said window, said slide having in one portion thereof a window opening of less extent than the aforesaid window and also having an index or pointer co-operating with the year schedule, means to adjust the slide lengthwise of the casing to vary the position of the slide window and pointer with respect to the year schedule, and a calendar sheet within the casing movable beneath the windows aforesaid in directions transverse to the direction of adjustment of the slide, said sheet bearing a plurality of supernumerary calendar blocks for both common and leap years and so arranged on the sheet that by adjustment of the sheet and slide the day of the week of any date within the scope of the device may be determined directly by simple adjustment as aforesaid, the slide bearing over its window designations of the day of the week.

4. Mechanism as set forth in claim 3 in which the means for adjustment of the slide comprises a threaded rod and a correspondingly threaded sleeve thereon, the rod being

journalized for rotation in the casing against endwise movement and the sleeve being fixed to the slide.

5. Mechanism as set forth in claim 3 in which the means for adjustment of the sheet comprises a pair of rollers geared together for simultaneous rotation in opposite directions, and locking means for the rollers serving to prevent unintended rotation thereof, said locking means including a multiple cam to lock the rollers by a limited turn thereof, and a shoe between a roller and the cam to make the latter effective to engage said roller.

6. Mechanism as set forth in claim 3 in which the means for adjusting the calendar sheet comprises a pair of rollers, one of which is provided with a locking hub, a brake shoe co-operating with said hub, and manually controlled means to control the position of the shoe for either locking the hub from rotation or releasing it for rotation, including a multiple cam operative through a limited turn according to the design of the multiple cam.

7. Mechanism as set forth in claim 3 in which the means for adjusting the calendar sheet comprises a pair of rollers upon which the sheet is wound and unwound respectively, and locking means for the roller comprising a serrated hub fixed to one of them, a similarly serrated shoe co-operating with the hub, a spring supporting the shoe and tending to release the shoe therefrom, a cam member backing up the shoe against the force of the spring to cause the shoe to engage the hub, a spindle manually operated to actuate the cam wheel, and means co-operating with the spindle to compel rotation thereof in but one direction.

8. A calendar as set forth in claim 1 in which the year indicating means includes a plate bearing on its surface a series of columns of dates, each column comprising a plurality of numbers of years, and a pointer movable by said obscuring means to indicate a column of years, whereby the years in a column are directly correlated with the selected month.

9. In a calendar of the character set forth, a calendar sheet bearing a number of supernumerary calendar blocks, means having a window in front of said sheet, means to move said sheet lengthwise to bring a desired calendar block to said window, means to cause a relative transverse movement between the sheet and the window to permit a desired portion of a calendar block to be seen therethrough according to the month selected, and year and month indicating means co-operating with said portion of the block to correlate the same coincident with the making of said longitudinal and transverse adjustments.

10. In a calendar of the character set

forth, a calendar sheet having a calendar block, window means in front of said sheet, said block having numerals arranged in vertical rows, and means to cause a relative 5 transverse movement between the window means and the sheet to permit a desired portion of the block to be visible therethrough, the numerals in the horizontal rows of the block being so related that a continuous set 10 of numerals for the days of a selected month

are always visible, means being provided to indicate the month, and year indicating means including a relatively fixed schedule in which years are arranged in vertical column, means being provided transversely 15 movable with said window means correlating the month and the year coincident with the transverse adjustment aforesaid.

In testimony whereof I affix my signature.
CHRISTIAN W. SCHLUSING.
